[57] CLAIM

The ornamental design for an oval holder for small metallic objects, as shown and described.

DESCRIPTION

FIG. 1 is a front perspective view of an oval holder for small metallic objects showing my new design.

FIG. 2 is a top plan view thereof.

FIG. 3 is a side elevation view thereof, the opposite side being substantially identical.

FIG. 4 is an end view thereof, the opposite side being substantially identical.

FIG. 5 is a bottom plan view thereof.

FIG. 6 is a front cross-sectional view taken along line 6—6 of FIG. 2; and

FIG. 7 is a cross-sectional view taken along line 7—7 of FIG. 2.

FIG.1

FIG. 2

FIG. 7
